UNITED STATES PATENT OFFICE

105,541

DESIGN FOR A COMBINED LIGHTER AND ASHTRAY

Gerrit Van Daam, Buffalo, N. Y.

Application January 5, 1937, Serial No. 66,904

Term of patent 7 years

To all whom it may concern:

Be it known that I, Gerrit Van Daam, a citizen of the United States, residing in Buffalo, in the county of Erie, State of New York, have invented a new, original, and ornamental Design for a Combined Lighter and Ashtray, of which the following is a specification, reference being had to the accompanying drawing, forming part thereof.

Fig. 1 is a view in perspective of the combined lighter and ashtray showing my design.

Fig. 2 is a side elevation showing the dome-shaped cover in open position.

I claim:

The ornamental design for a combined lighter and ashtray, as shown and described.

GERRIT VAN DAAM.
